DISPENSING CONTAINER

Alfred J. Chamberlain, Wauwatosa, Wis.

Application June 28, 1937, Serial No. 150,709

6 Claims. (Cl. 221—11)

This invention relates to an improvement in dispensing fittings for liquid containers and generally aims to provide a fitting of this character which is self-venting and also embodies the feature of a disappearing spout.

Another object of the invention is to provide a dispensing fitting of this character which is simple and durable in its construction, compactly organized, reliable and efficient in use, easily manipulated, and easy and comparatively inexpensive to manufacture.

Another important object of the invention is to so construct and organize the nozzle and spout as to insure the effective operation of the self-venting feature in actual practice.

Other objects and advantages reside in certain novel features of the construction, arrangement and combination of parts which will be herein-after more fully described and particularly pointed out in the appended claims, reference being had to the accompanying drawing forming a part of this specification and in which:

Fig. 1 is a fragmentary view in central vertical longitudinal section illustrating a portion of a top of a container equipped with a dispensing fitting embodying the invention and showing the spout in its extended or operative position;

Fig. 2 is a view similar to Fig. 1 but illustrating the disappearing spout hanging down inside the container in its inoperative position and showing a closure cap applied to the outlet fitting;

Fig. 3 is a fragmentary view illustrating the dispensing fitting in top plan;

Fig. 4 is a sectional view taken on line 4—4 of Fig. 1; and

Fig. 5 is a similar view taken on line 5—5 of Fig. 1, parts being broken away and parts being shown in elevation for the sake of illustration.

Referring to the drawing the numeral 10 designates generally a metal container which may be of any suitable construction and which is provided with a top 11, preferably inset in the manner indicated in Figures 1 and 2. The top 11 is provided with an oblong opening equipped with a similarly shaped nozzle designated generally at 12. The nozzle 12 has a vertically disposed upper portion 13 provided around its upper edge with a rolled bead 14 and has an outwardly and downwardly inclining or flaring lower portion 15 formed as an integral continuation of the upper portion 13.

The flaring lower portion 15 has a horizontally disposed marginal flange 16 which is interseamed

as indicated at 17 with the margin of the opening in the top 11 of the container.

A removable closure cap 18 of any suitable construction is provided for the nozzle 12.

A disappearing spout designated generally at 20 is hingedly connected as at 21 to the outlet fitting adjacent one end thereof so that the spout may hang downwardly in the can as illustrated in Figure 2 to permit of application of the closure cap 18, or may be swung upwardly and outwardly to the pouring position shown in Figure 1 when cap 18 is removed. The spout 20 is generally U-shaped in horizontal cross section as will be understood from the drawing, particularly Figure 3, and is made up of side walls or wings 22 disposed in spaced parallel relation and connected transversely at their forward ends by the curved end portion 23 of the spout. The spout is so shaped in vertical cross section that its side wings 22 and curved forward end wall 23 all have a vertical portion 24 designed to snugly fit against the vertical portion 13 of the nozzle and a downwardly and outwardly flaring portion 25 designed to snugly interfit with the flaring portion 15 of the nozzle when the spout is swung to its pouring position. Rigid lugs or ribs 26 are pressed out from or attached to the vertical portion 13 of the nozzle and are so positioned as to engage the curving edges 22' of the spout so that as the spout is swung up to its pouring position these lugs or ribs will force the spout forwardly to cause it to firmly interfit with the portion of the nozzle with which it is associated. In other words, the spout is so designed, dimensioned and proportioned that its side wings 22 have tight spring friction engagement with the inner wall of the nozzle as the spout is swung to its operative position.

The major axis of the outlet nozzle is substantially longer than the corresponding axis of the spout so that with the spout in its pouring position there is a substantial venting space 30 rearwardly thereof. The hinge connection 21 is sufficiently loose or "sloppy" to allow the ribs 26 to exert the camming action described. This action of the lugs plus the fact that the wings of the spout have snug frictional engagement with the outlet fitting releasably retains the spout in its pouring position. In this connection, it will be noted that the forward portion of the spout overhangs the bead 14 of the forward portion of the nozzle and when retained in this relation, will not drop back into the container. The spout, like the container proper is constituted of sheet metal and hence is possessed of the proper

amount of still resilience to enable it to be shaped as shown and yet retain its shape and function as described in use.

An important feature of the present invention 5 resides in the structure and organization of the spout and its nozzle to insure self-venting at all times and yet provide for the pouring of as large a stream from the container as is practically desirable. When a person tips the container to 10 pour liquid therefrom, the spout being in its extended or pouring position, there is available a spout of ample proportions to allow a stream of any practical or desirable size to be poured therefrom, this following from the substantial extent 15 of the side wings of the spout as well as its other dimensions. Moreover, there is a substantial space between the rearmost portions of the edges of the wings of the spout and the rear end of the nozzle so that at the rear of the nozzle there is 20 always a substantial venting opening. These features, together with the fact that the extent of the spout and the extent of the venting opening are always within the full view of the person using the container, will of themselves preclude any 25 possibility of the container being so far tilted as to interfere with the effective self-venting. In fact, this is practically impossible because any attempt to exceed the capacity of the spout and consequently to obstruct the venting opening at 30 the rear thereof would, if made, result in spilling of the liquid.

While I have shown and described one construction in which the invention may be advantageously embodied, it is to be understood that 35 the construction shown has been selected merely for the purpose of illustration or example and that various changes in the size, shape and arrangement of the parts may be made without departing from the spirit of the invention or the 40 scope of the subjoined claims.

The invention claimed is:

1. A dispensing fitting for containers comprising a nozzle secured to the container and projecting therefrom, said nozzle being generally of 45 oblong form, a spout of generally U-shaped form and comprising spaced side wings and a curved connecting portion at one end of the side wings, means mounting the spout for shiftable movement with respect to the nozzle so that it may be 50 projected therefrom in pouring position or may be disposed within the container, the rearmost portions of the edges of the side wings of the spout being spaced at substantial distance from the rear end of the nozzle whereby to provide an 55 unobstructed venting opening of substantial area through the nozzle and to the rear of the spout in all operative pouring positions of the container.

2. A dispensing fitting for containers comprising a nozzle adapted to be secured to and project 60 from the container, said nozzle being generally of oblong form, a spout of generally U-shaped form and comprising spaced side wings and a curved connecting portion at one end of the side wings, a loose hinge connection between the inner edge 65 of said curved connecting portion and the inner edge of one end of the nozzle whereby the spout may be disposed within the container or swung to a position projecting through and beyond said nozzle, the rear edges of the wings being curved, and rigid camming lugs secured to the nozzle and 70 cooperative with the curved edges of the wings for

forcing the spout into tight frictional engagement with the nozzle in the extended position of the spout.

3. A dispensing fitting for containers comprising 5 a nozzle secured to the container and projecting therefrom, said nozzle being of oblong form, a spout of generally U-shaped form hingedly supported for pivotal movement with respect to the nozzle and adapted to hang inside the container or to be extended through and beyond the 10 nozzle, said nozzle and said spout having interengageable vertical portions and also interengageable downwardly and outwardly flaring portions, and rigid camming lugs carried by the nozzle and co-operable with the rear portions of the spout to 15 force said interengageable parts into tight frictional contact.

4. A dispensing fitting for containers comprising 20 a nozzle adapted to be secured to and project from the container, a disappearing spout, a loose hinge connection between one end of the spout and one end portion of the nozzle whereby the spout may hang down into the container and may be swung up to a position to which it projects therefrom, said spout and said nozzle having 25 interengageable portions in the projecting position of the spout, and rigid means carried by the nozzle and cooperable with the spout for forcing said interengageable portion into tight frictional contact.

5. A dispensing fitting for containers comprising 30 a nozzle secured to the container and projecting therefrom, said nozzle being generally of oblong form, a spout of generally U-shaped form and comprising spaced side wings and a curved 35 connecting portion at one end of the side wings, means mounting the spout on the nozzle so that it may be projected therefrom in pouring position or may be disposed within the container, means co-acting with the side wings of the spout 40 to aid in maintaining it in pouring position, the rearmost portions of the edges of the side wings of the spout being spaced at substantial distance from the rear end of the nozzle whereby to provide an 45 unobstructed venting opening of substantial area through the nozzle and to the rear of the spout in all operative pouring positions of the container.

6. A dispensing fitting for containers comprising 50 an elongated nozzle adapted to be secured to and project from the container, a spout of generally U-shaped form and comprising spaced side wings and a connecting portion between said wings at one end thereof, a hinge connection between the inner edge of said connecting portion and the inner edge of one end of the nozzle whereby the spout may hang down within the container or may be swung in a position projecting through and beyond said nozzle, the side wings frictionally engaging the sides of the nozzle, the rearmost portions of the edges of the wings of the spout terminating in spaced relation to the adjacent end of the nozzle to define an unobstructed venting opening in all operative pouring positions of the container, the rear edges of said wings being 55 curved, and rigid means carried by the nozzle and co-acting with the curved edges of the wings for forcing the spout into tight frictional engagement with the nozzle in the extended position of the spout.

ALFRED J. CHAMBERLAIN. 70
